LOW FREQUENCY TONE CONTROL SYSTEM

Arthur C. Stocker, Haddon Heights, N. J., assignor to Radio Corporation of America, a corporation of Delaware

Application March 31, 1937, Serial No. 134,108

7 Claims. (Cl. 179—171)

The present invention relates to a low frequency tone control system for an audio frequency amplifier or signal transmission channel, and has for its object to provide an improved tone control system of that character wherein a minimum number of low cost circuit elements are provided and which is not restricted to close tolerances in the electrical values of said circuit elements.

It is also a further object of the present invention, to provide a low frequency tone control system for audio frequency amplifiers and the like, wherein, through the medium of a single potentiometer control means, both attenuation and augmentation of the low frequency end of the audio frequency response range of the amplifier may be provided.

It is a still further object of the present invention, to provide a low frequency tone control system which is adapted for use as a grid circuit attenuator and as part of an interstage coupling network which includes a single control means for attenuating and augmenting the low frequency portion of the response characteristic of the amplifier.

The invention will, however, be better understood from the following description, when considered in connection with the accompanying drawing, and its scope will be pointed out in the appended claims.

In the drawing,

Figure 1 is a schematic circuit diagram of an audio frequency amplifier having an interstage coupling network embodying the invention.

Figure 2 is a graph or vector diagram illustrating the amplitude relation between potentials developed in the coupling network of Fig. 1.

Figure 3 is a graph showing curves illustrating the operating range and tone control characteristics of the low frequency tone control network of Fig. 1, and

Figure 4 is a similar graph showing curves illustrating the low frequency response characteristic in percentage, for the limits of the control range provided by the circuit of Fig. 1.

Referring to Fig. 1, 5 and 6 are first and second stage audio frequency amplifier tubes provided with an interstage coupling means which may be of any suitable type and which, in the present example, is of the resistance coupling type having a plate resistor 7 in the output circuit 8 of the first stage 5 and a plate supply filter comprising a series resistor element 9 and shunt bypass capacitor 10 to chassis or ground 11 between the plate resistor 7 and the anode supply lead,

indicated at 12. The coupling capacitor for the resistance coupling network is indicated at 13 and serves to convey signals to the grid circuit 14 of the second stage 6, through a low frequency tone control network comprising a shunt circuit 5 connected across the audio frequency channel or output circuit of the tube 5 through said coupling capacitor.

The shunt circuit comprises two series resistors 15 and 16 with a capacitive reactance in series 10 between them and provided by a capacitor 17. A potentiometer device 18 is connected in parallel with the capacitor 17 and the movable contact 18 thereof is connected to the grid circuit 14.

Grid bias potential is applied to the grid through 15 a grid supply filter comprising a series filter resistor 20 connected between a bias supply lead 21 and the low potential terminal 22 of the resistor 16. An audio frequency by-pass capacitor 23 is connected between the terminal 22 and chassis or ground 24. The audio frequency circuit is completed to cathode of the amplifier 6 through a ground connection indicated at 25.

The tone control network comprising the resistors 15, 16 and 18 and the capacitor 17 is an attenuator, the attenuation of which varies with frequency, and the manner of this variation being controllable by the resistor or potentiometer 18. The values of the resistors 16 and 15 and of the capacitor 17 determine the amount of low frequency correction and the highest frequency affected. The control resistor or potentiometer 18 has no function other than that of control so long as its total value is several times greater than the reactance of the capacitor 17 at the lowest frequency to be considered.

Assuming the resistances of the resistors 16, 18 and 15 to be R_4 , R_5 and R_6 respectively and the reactance of the capacitor 17 to be C_3 , the latter is designed to be relatively small compared to the resistances R_4 and R_6 when the applied signal frequency is above a predetermined high value, that is, above the low frequency tone control range desired. Then the voltage

$$e = E \frac{R_4}{R_4 + R_6}$$

approximately and is independent of the setting of R_5 , assuming that the alternating current potential applied to the tube 6 is indicated at e , 50 and that the available signal potential from the first stage amplifier is indicated at E .

As the frequency of the signals transmitted through the amplifier is reduced, the voltages across R_4 and R_6 drop and that across C_3 rises, 55

the vector sum always being equal to E. The distribution is substantially as shown in Fig. 2 where in a and c represent the voltages across R₄ and R₆ (R₄ being somewhat larger than R₆ in this case), and b represents the voltage across C₃. The voltage e is then the vector sum of a and a portion of b, the portion being determined by the setting of the contact 19 on R₅.

The value of e may vary from a to e₅ in Fig. 2, as the potentiometer contact 19 is moved from the lower potential end of the resistor 18 through to the higher potential end thereof. With the contact 19 at the lower potential end of the tone control resistor 18, thereby including only the resistance R₄ in the grid circuit, the voltage a will be equal to the voltage e and it is obvious that the frequency characteristic of the output will drop at the lower frequency end of the audio frequency range. The ratio of the voltage e to the voltage E is shown in Fig. 3 with respect to frequency and in this case

$$\frac{e}{E} = \frac{R_4}{R_4 + R_5 + R_6}$$

When the contact 19 is moved to the upper or high potential end of the tone control resistor 18, it is obvious that the frequency characteristic of the output will rise at the lower frequency end of the audio frequency range. This is also shown in the curve of Fig. 3 and the voltage ratio is

$$\frac{e}{E} = \frac{R_4 + R_6}{R_4 + R_5 + R_6}$$

The low frequency limits in either case are indicated in Fig. 3 by the lines 30 and 31 and the shape of the response characteristic for attenuating the low frequency end of the audio frequency range is indicated at 32 while the augmentation of low frequencies provided is indicated by the curve 33. The normal high frequency response or limit of response is indicated by the line 34.

If the contact 19 is moved to provide the vector voltage e₃ of Fig. 2, the voltage e will not be varied, by the variation in frequency of an applied signal. This may be seen by referring to Fig. 2 wherein, at infinite frequency,

$$e = E \frac{a}{a + c}$$

and lies along the vector E. As the frequency is reduced the junction of vectors a and b moves to the right and down following a semi-circular path to "0" at zero frequency. The junction of the vectors b and c moves to E. The vector b always crosses the vector E at the same place, the vector b swinging around this point and the two ends of the vector b remaining always in the same ratio. If this ratio is that chosen by the contact 19 on the resistance R₅, e will remain a constant portion of E regardless of frequency.

The limits of response of the low frequency control means thus provided is indicated in Fig. 4 by the curves 35 and 36. It is not necessary to maintain the resistance of R₅ higher than the reactance of the tone control capacity C₃ at all frequencies, although in the present example and as a preferred arrangement in the network shown, R₄ and R₆ are made equal to 10,000 ohms, and with a capacity at C₃ of .1 mfd. the resistor R₅ has a value of .5 megohm. The effect of using a lower resistance at R₅ is to lessen the slope of the response characteristic at the low frequency end of the response range which gradually is reduced to zero at some very low frequency be-

yond the range of operation normally utilized in an audio frequency amplifier.

From the shape of the resulting curves in Figs. 3 and 4, it will be seen that the low frequency response characteristic may be varied between 5 relatively wide limits to increase or decrease the low frequency response continuously, by operation of the single contact 19.

In any circuit, the reactance of the capacity C₃ to signal frequencies above the range in which 10 low frequency tone control is desired, is made relatively low with respect to the series resistances R₄ and R₆ on either side of it in the shunt circuit. As has been pointed out, the resistance of the shunt potentiometer is preferably substantially greater than the reactance of the capacity C₃ at the lowest frequency in the range of frequencies to be controlled.

This system permits selection of either an attenuated, a flat, or an augmented low frequency 20 response without recourse to resonant phenomena or complicated circuits.

When the resistors R₄ and R₆ in the tone control circuit are of the same order or lower than the output coupling resistor 7 in the preceding 25 stage, the latter is unloaded as the frequency of the transmitted signals is lowered. This is for the reason that the reactance of the series capacity C₃ rises, then by decreasing the shunt load created by the circuit R₄—C₃—R₆ across the 30 resistor 7.

The effect of this is to cause E to rise and thereby augment the low frequency response.

From the foregoing description, it will be seen that a low frequency tone control network 35 may be provided as an interstage coupling means and may be operated by a single control element to attenuate or accentuate low frequency response in a predetermined frequency range without appreciably affecting the high frequency response. 40

Furthermore, as above pointed out, by the variable loading effect the low frequency response may be increased automatically as the frequency of the transmitted signals is lowered.

I claim as my invention:

1. The combination with an audio frequency signal transmission circuit, of a low frequency tone control network connected in shunt with said circuit and comprising two resistance elements of the order of the resistance of the 50 transmission circuit connected in series between the high and low potential sides of said circuit, means providing a capacity in series with and connected between said resistance elements, the capacitive reactance thereof being relatively low 55 with respect to the resistance of said resistance elements in a higher frequency range above a predetermined upper limit of the low frequency tone control range, an output circuit, and means including a potentiometer device directly in shunt 60 with said capacity means for variably including said capacity means in said last named circuit.

2. The combination with an audio frequency signal transmission circuit, of a low frequency tone control network connected in shunt with 65 said circuit and comprising two resistance elements of the order of the resistance of the transmission circuit connected in series between the high and low potential sides of said circuit, means providing a capacity in series with and connected between said resistance elements, the capacitive reactance thereof being relatively low 70 with respect to the resistance of said resistance elements in a frequency range above a predetermined upper limit of the low frequency tone con- 75

trol range, whereby the shunt load on the transmission circuit is reduced with decreasing frequency, thereby augmenting the low frequency response.

- 5 3. The combination with an audio frequency signal transmission circuit, of a low frequency tone control network connected in shunt with said circuit and comprising two resistance elements of the order of the resistance of the transmission circuit connected in series between the high and low potential sides of said circuit, means providing a capacity in series with and connected between said resistance elements, the capacitive reactance thereof being relatively low 10 with respect to the resistance of said resistance elements in a frequency range above a predetermined upper limit of the low frequency tone control range, a potentiometer resistor connected in shunt with said capacity means having a resistance relatively high with respect to the reactance of said capacity means at the lowest frequency in said tone control range, an output contact movable along with potentiometer resistor, and a signal output circuit connected with said 15 contact and the low potential side of the signal transmission circuit.
4. The combination with an audio frequency signal transmission circuit, of a low frequency tone control network connected in shunt with said circuit and comprising two resistance elements of the order of the resistance of the transmission circuit connected in series between the high and low potential sides of said circuit, means providing a capacity in series with and 20 connected between said resistance elements, the capacitive reactance thereof being relatively low with respect to the resistance of said resistance elements in a frequency range above a predetermined low frequency, and a tone control potentiometer connected in shunt with said capacity element and having a variable output contact connected with said amplifier tube to apply signals thereto, said 25 potentiometer having a resistance relatively high with respect to the reactance of said capacity element at the lowest frequency to be controlled.
5. In an audio frequency amplifier, the combination with an amplifier tube having an input grid circuit, of an interstage coupling network 30 providing tone control means in said input circuit, said network including a coupling resistor for applying audio frequency signals across said last named circuit, a pair of resistance elements having a resistance value not greater than said coupling resistor and connected in series in said last named circuit, a capacity element in series with and connected between said resistance elements providing reactance relatively low with respect to the resistance of said resistance elements in a frequency range above a predetermined 35 low frequency, and a tone control potentiometer connected in shunt with said capacity element and having a variable output contact connected with said amplifier tube to apply signals thereto, said potentiometer having a resistance relatively high with respect to the reactance of said capacity element at the lowest frequency to be controlled.
6. In an audio frequency amplifier, the combination with an amplifier tube having an input grid circuit, of an interstage coupling network 40 providing tone control means in said input circuit, said network including a coupling resistor for applying audio frequency signals across said last named circuit, a pair of resistance elements having a resistance value not greater than said coupling resistor connected in series in said last named circuit, a capacity element in series with and connected between said resistance elements 45 providing reactance relatively low with respect to the resistance of said resistance elements in a frequency range above a predetermined low frequency, and a tone control potentiometer connected in shunt with said capacity element having a variable output contact connected with said amplifier tube to apply signals thereto, said potentiometer having a resistance relatively high with respect to the reactance of said capacity element at the lowest frequency to be controlled, 50 and means providing a low impedance signal path to ground each for the low potential end of said coupling resistor and one of said series connected resistors.

to

$$\frac{e}{E} = \frac{R_4}{R_4 + R_5 + R_6}$$

50 where E is the signal input voltage, e is the signal output voltage, R_4 and R_6 are the resistance of the series connected resistance elements, and R_5 is the resistance interposed across the capacitive reactance.

- 55 5. In an audio frequency amplifier, the combination with an amplifier tube having an input grid circuit, of an interstage coupling network 60

providing tone control means in said input circuit, said network including a coupling resistor for applying audio frequency signals across said last named circuit, a pair of resistance elements having a resistance value not greater than said coupling resistor and connected in series in said last named circuit, a capacity element in series with and connected between said resistance elements, and a tone control potentiometer connected in shunt with said capacity element and having a variable output contact connected with said amplifier tube to apply signals thereto.

6. In an audio frequency amplifier, the combination with an amplifier tube having an input grid circuit, of an interstage coupling network 15 providing tone control means in said input circuit, said network including a coupling resistor for applying audio frequency signals across said last named circuit, a pair of resistance elements having a resistance value not greater than said coupling resistor and connected in series in said last named circuit, a capacity element in series with and connected between said resistance elements providing reactance relatively low with respect to the resistance of said resistance elements in a frequency range above a predetermined 20 low frequency, and a tone control potentiometer connected in shunt with said capacity element and having a variable output contact connected with said amplifier tube to apply signals thereto, said potentiometer having a resistance relatively high with respect to the reactance of said capacity element at the lowest frequency to be controlled.

7. In an audio frequency amplifier, the combination with an amplifier tube having an input grid circuit, of an interstage coupling network 25 providing tone control means in said input circuit, said network including a coupling resistor for applying audio frequency signals across said last named circuit, a pair of resistance elements having a resistance value not greater than said coupling resistor connected in series in said last named circuit, a capacity element in series with and connected between said resistance elements 30 providing reactance relatively low with respect to the resistance of said resistance elements in a frequency range above a predetermined low frequency, and a tone control potentiometer connected in shunt with said capacity element having a variable output contact connected with said amplifier tube to apply signals thereto, said potentiometer having a resistance relatively high with respect to the reactance of said capacity element at the lowest frequency to be controlled, 35 and means providing a low impedance signal path to ground each for the low potential end of said coupling resistor and one of said series connected resistors.

ARTHUR C. STOCKER. 60
